3 Sheets-Sheet 2

This technical drawing illustrates a complex mechanical assembly, likely a pump or valve mechanism. The drawing is oriented vertically, showing a central vertical axis and various components extending from it. Key features include:

- A large rectangular housing at the top with a handle and a circular component labeled 60.
- A central vertical shaft with a gear assembly.
- Several circular components, some with internal numbers like 13, 16, 17, 18, 21, 23, 24, 29, 30, 33, 34, 35, 36, 37, 38, 39, 40, 41, 42, 43, 44, 45, 46, 47, 48, 49, 50, 51, 52, 53, 54, 55, 56, 57, 58, 59, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, and 96.
- A stepped base at the bottom.
- A signature in the bottom right corner that reads "George BY J. J. ae".

UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed May 13, 1925. Serial No. 29,874.

My invention relates to typewriting machines, and more particularly to tabulating mechanism therefor.

Generally stated, the main object of my invention is to provide a simple and highly efficient tabulating mechanism comprising but few parts and which may be manufactured and assembled in the machine at small cost.

More specifically stated, an object of the invention is to provide (a) a tabulator mechanism, (b) carriage anti-rebound mechanism and (c) carriage retarding mechanism in which the parts are simple in construction, cheap to manufacture and install, and coact to operate in a highly effective manner to attain the desired results.

To the above and other ends which will hereinafter appear, my invention consists in the features of construction, arrangements of parts and combinations of devices set forth in the following description and particularly pointed out in the appended claims.

In the accompanying drawings wherein like reference characters designate corresponding parts in the different views—

Figure 1 is a fragmentary fore-and-aft vertical sectional view of a typewriting machine equipped with the mechanism of my invention; the section being taken on the line 1—1 of Fig. 2 with parts removed and looking in the direction of the arrows at said line.

Figure 2 is a fragmentary top plan view of a portion of the same.

Figure 3 is a fragmentary rear elevation of the machine with parts in section and parts broken away.

Figure 4 is a fragmentary detail rear elevation showing a portion of the tabulator mechanism as the parts appear just before a column stop reaches the co-acting projected tabulator stop and the carriage is moving in the direction of the arrow.

Figure 5 is a like view of the same showing the parts as they appear just after a column stop has reached and engages the projected tabulator stop.

I have shown my invention, in the present instance, incorporated in a machine resembling the No. 12 Remington, but have illustrated only so much of said machine as is necessary to arrive at an understanding of my invention in its embodiment therein.

It should be understood, however, that the

invention may be included in various styles of typewriting or like machines.

The frame of the machine comprises a base 1, corner posts 2, and a top plate 3. A carriage 4 of the usual construction is supported on bearing rollers to travel from side-to-side of the machine over the top plate. The bearing rollers at the rear of the carriage are indicated by the reference numeral 5. This carriage supports a platen 6 and is moved in the direction of its feed, or from right to left, by a spring drum 7 connected to the carriage by a pull band 8.

A feed rack 9 is secured by screws 10 to a cross bar 11 having forwardly projecting arms 12 pivoted at 13 on upstanding lugs 14 on brackets 15. These brackets are secured by screws 16 to the rear cross bar 17 of the carriage, one near each end of said cross bar. The bar 11 near the center thereof carries an adjustable screw stop 18 which coacts with a companion stop 18^a secured to the rear cross bar of the carriage by screws 19 and a plate 20. In the present instance this stop 18^a is shown as forming a plate-like foot piece of an upwardly and rearwardly extending integral bracket arm 21, for purposes which will hereinafter appear. The stops 18 and 18^a coact to limit the downward movement of the feed rack into engagement with the teeth of a feed pinion 22. Said pinion constitutes part of the usual carriage escapement mechanism, being operatively connected to the escapement wheel (not shown) which controls the step-by-step letter feed movement of the carriage.

A double ended leaf spring 23 is secured at the middle thereof to the rear cross bar of the carriage by the screws 19, plate 20 and foot piece 18^a. Each free end of this leaf spring is bent down at its sides, as shown in Fig. 1, and extends over and bears down on a horizontally disposed pin 24 carried by the bar 11. The pressure of this spring, therefore, tends to move the feed rack down into engagement with the feed pinion 22 and hold it in such engagement.

Each bracket 15 is also provided with a rearwardly extending arm 25, on which arms is adjustably secured in the usual manner a column stop bar 26 carrying a series of column stops 27, 28 and 29. Each column stop, in the present instance, is made of sheet metal and is bifurcated in order that it may be detachably secured in the interdental 110.

spaces 30 on opposite sides of the bar, and thus may be adjusted to any letter space interval along the bar.

- Each of the bracket arms 25 carries an off-set additional bracket arm 31 tapped to receive a screw stop 32 that may have a lock nut 33 threaded onto the top end portion thereof and against the bracket arm 31 to hold the screw stop in its adjusted position.
- 10 Each of these screw stops overlies the upper edge of the feed rack 9, near one end thereof. These stops constitute limiting means for limiting the upward releasing movement of the feed rack against the force of the spring 23 when the rack is disengaged from the feed pinion 22, for purposes which will hereinafter more clearly appear. On carriages of standard length it will suffice to employ the two screw stops 32, each co-acting with the rack near one end thereof. However, when long carriages are used I prefer to employ a third screw stop 34 located about midway in the length of the carriage and co-acting with the top of the feed rack intermediate the ends thereof. This third stop 34 is mounted in a manner which will presently appear.

A bracket 35 which may be made of sheet metal has feet 36 apertured to receive the shanks of headed screws 37, received at their threaded ends in tapped openings in the top plate 3 of the machine. This bracket has an inwardly extending arm 38 that terminates in a rearwardly bent end portion 39 near the fore-and-aft vertical median plane of the machine. This end portion 39 has a vertically disposed slot 40 therein. The upper and lower end walls 41 and 42 of this slot constitute arresting means for limiting respectively the up and down rectilinear movements of a combined tabulator and anti-rebound stop into and out of effective position, as will presently appear. This combined stop is designated as a whole by the reference numeral 43 and comprises a slide or plate-like member 44 mounted on the left-hand face of the bracket end 39. Headed rivets 45 and 46 are riveted at their right-hand ends to the slide 44, and at their left-hand ends to a second plate 47. The intervening shouldered portion of each rivet passes freely through the slot 40 to slide up and down therein and maintain the members 44 and 47 properly spaced apart, and secure the stop member 43 for sliding movement on the fixed bracket 35. When the member 43 has been fully projected to effective position, as shown in Fig. 5, the upper rivet 45 co-acts with the upper end wall of the slot 40 to limit the further upward movement of said member. In the return of the member 43 to lowermost or normal position the lower rivet 46 co-acts with the bottom wall of the slot 40 to arrest said member. Extending to the left from the

plate 47, and at right-angles thereto, is an integral sheet metal arm 48 which carries a rearwardly projecting pin 49 through which motion is transmitted to the member 43 from a tabulator key, as will hereinafter appear.

The member 43 has a tabulator stop 50 that has an abrupt right-hand face 51 on one side and a beveled face or end 52 on the left-hand side. A laterally projecting arm 53 on the member 43 carries an anti-rebound stop or device 54 which is beveled on its right-hand face 56 and has an abrupt flat face 57 on the left-hand side thereof. There is an intervening space or slot 58 between the face 51 of the tabulator stop and the face 57 of the anti-rebound stop, which space is of a width slightly in excess of the thickness of each of the column stops. It will be observed, moreover, that the upper edge of the stop 50 is at a slightly higher elevation than the top edge of the stop 54.

Motion is transmitted from the tabulator key to project the combined stop member 43 to effective position by the following means:

A tabulator key 59 is arranged at one side of the keyboard on the forward end of a key lever 60 fulcrumed at the rear end thereof on the usual fulcrum bar 61 and guided in slots of guide combs 62 and 63. A returning spring 60^a is connected at one end to the key lever 60 and aids in returning said lever and the parts controlled thereby to normal position. This key lever carries a laterally projecting pin 64 by which it is detachably pivoted with the aid of a cotter pin 65, to the lower end of a bent sheet metal link 66. This link extends rearwardly and upwardly from its point of pivotal connection with the key lever, and is twisted at 67 so that the upper end portion of the link lies in a lateral plane, while the lower end thereof lies in a fore-and-aft plane. The upper end of the link is pivoted by a shouldered pivot screw 68 to the outer end of an arm 69, the forward end of the screw 68 engaging a lock nut 70. The arm 69 is mounted intermediate its ends on a shouldered screw 71 received at its threaded end in a tapped opening in the left-hand arm of a lever 72; the screw 71 being held by a lock nut 73. The inner end of the arm 69 has a slot 74 struck in an arc around the pivot screw 71 as a center. The threaded shank of a headed binding screw 75 passes freely through a slot 74 and is received in a tapped opening in the lever 72 and extends therethrough for engagement with a lock nut 76. The lever 72 is pivoted intermediate its ends on a shouldered pivot screw 76, received at its threaded end in a tapped opening in the bracket 35 and held in place thereon by a lock nut 77. By these means the lever 72 and its arm 69 constitute in

effect a two-part lever, one part of which may be adjusted relatively to the other. Thus, by loosening the screw 75, the outer end of the arm 69 may be raised or lowered 5 to bring the tabulator key to the proper elevation on the keyboard, while the inner end of the lever 72 and the parts controlled thereby remain in the normal position, shown in Fig. 3. The screw 75 may then 10 be tightened to connect the members 69 and 72 in their adjusted relation to move together as one part.

The lever 72 is provided at its inner end with a finger 78 that overlies the pin 49 and 15 is in contact therewith when the parts are in normal position, shown in Fig. 3. A leaf spring 79 has a foot-piece 80 bent at right angles to the plane of the body thereof, and this foot-piece is secured to the rear side of 20 the lever 72 by screws 81. The inner free end of the spring extends forwardly at 79^a (see Fig. 2) where it underlies the pin 49. The power of this spring 79, when the parts are in the normal position, shown in Fig. 3, 25 exerts a comparatively light upward pressure on the pin 49 to hold it normally in engagement with the finger 78 on the lever 72.

The sheet metal lever 72 is also provided with a forwardly extending arm 82 (see 30 Fig. 2) that may be formed integral therewith. This arm terminates in a contact shoe, rack lifter or carriage releasing device or member 83 that also acts as a brake shoe when actuated. This member 83 is prefer- 35 ably curved in cross section to present an upper convex contact face where it underlies the teeth of the feed rack 9, as best shown in Fig. 5. A wire returning spring 84 is coiled around the shank of a headed 40 screw 85 secured to and projecting from the rear side of the bracket 35. One arm 86 of this spring bears down against the arm 82, whereas the other arm 87 of the spring bears down against a foot piece 36 of the bracket 45 35. The force of this spring is therefore exerted to return the entire tabulator to the normal, Fig. 3, position, including the tabulator key, the combined stop 43 and all of the intervening parts.

50 The operation of the mechanism of my invention is as follows:

A depression of the tabulator key 59 is effective to draw down the outer end of the lever 72 and elevate the inner end thereof. 55 This results in carrying the spring 79 up and transmitting through said spring an upward sliding rectilinear movement to the combined stop member 43 by the co-operation of said spring with the pin 49. This 60 upward motion of the stop member 43 continues until it is arrested by its independent arresting means 41, 45. However, the motion of the lever 72 under control of the tabulator key may continue against the resistance of the spring 79 which is being flexed

at this time. During the motion of the lever 72 the rack releasing device 83 thereon is carried up, lifting the feed rack 9 out of engagement with the feed pinion 22. The independent motion of the lever 72 which, 70 as described above, takes place after the stop member 43 has been arrested in projected position, continues until the feed rack 9 has been moved up to the position where it is arrested by its independent arresting means 75 or screw stops 32, and also by the stop 34 if the latter be employed. Such stops are the only thing that limit the depression of the tabulator key and the actuating movement of the lever 72 controlled thereby. It 80 will be understood therefore, that after the feed rack is arrested in its releasing movement by said stops, the harder the pressure exerted on the tabulator key the greater will be the force exerted by the carriage releasing member 83 against the feed rack. At this time, therefore, the member 83 will act as a positively applied brake shoe to retard the carriage in its otherwise free movement across the machine. Therefore, the speed 85 of the carriage in this movement will depend on the application of the brake and the amount of pressure exerted by the operator on the tabulator key. This latter, by reason of the long leverage provided by the 90 key lever 60, need not be very great, and the operator will soon learn to apply just the requisite amount of pressure to the key to properly retard the tabulating movement of 95 the carriage.

The first part of the depression of the tabulator key projected the stop member to effective position, as above explained, and held it in such position under the action of the spring 79 thereon. Assuming that the carriage is being tabulated in the direction of its feed, or from right to left, the effect of the movement of the stop member 43 was to bring the bevel face 56 of the anti-rebound stop 54 into the path of the first of 100 the approaching column stops 27, 28 and 29. The carriage having been released and the brake applied by the same act of depressing the tabulator key, the carriage 105 will travel to the left until it co-acts with the bevel face 56 of the anti-rebound stop 54, as shown in Fig. 4. The effect of this co-operation of the stops in question is to force the member 43 down against the force of the spring 79 without, however, affecting the braking action which is still maintained on the carriage. In Fig. 4 the parts are shown displayed as they appear when the stop member 43 is almost depressed to its 110 lowermost position against the action of the spring 79, and just before the stop 29 moves into register with the slot 58. When this does occur the stop member 43 will be quickly moved up by the flexed spring 79 to the Fig. 5 position. At this time, the col- 115 120 125 130

umn stop 29 will engage the abrupt face 51 of the tabulator stop 50 and the carriage will be arrested. Any rebound of the carriage at this time is limited by the abrupt 5 face 57 of the anti-rebound stop 54 coacting with the right-hand face of the column stop 29. It is unnecessary to absolutely prevent all rebound of the carriage, but merely to limit the extent of such rebound to less than 10 a letter space distance. Fig. 5 shows the parts as they appear after the tabulating operation described has been completed. The operator now releases the tabulator key and the parts will be returned to the normal 15 Fig. 3 position by the springs 84 and 60^a. During the return movement of the parts the stop member 43 will be held projected by the spring 79 while the lever 72 is moving back to normal position, and until the 20 finger 78 engages the pin 49 to move the stop member 43 downwardly. This lead in the movement of the lever 72 enables the feed rack 9 to be moved down into engagement with the feed pinion 22 before the stop 25 member 43 releases the engaged column stop. This, of course, means that the carriage is restored to control of its escapement mechanism before the tabulator mechanism releases the control of the carriage. 30 From an inspection of Fig. 5 it will be understood that the construction and arrangement of the parts are such that the column stops may be adjusted relatively one to another so that they are separated two 35 letter spaces apart without interfering with the operation of the tabulator mechanism. This affords a jump of the carriage of one letter space, the minimum amount required in practice. However, the parts may be so 40 proportioned that the column stops may be set at letter space intervals without interfering with the operation of the tabulator.

I have described the operation of the tabulator in controlling the carriage in its 45 movement from right to left. It should be understood, however, that the mechanism also is capable of use for backward tabulating, in which the carriage is moved from left to right to tabulating position. At such 50 time the tabulator operates substantially as before except that the carriage is pushed from left to right. At this time, however, the first approaching column stop co-acts with the bevel face 52 of the stop 50 and 55 depresses the stop member 43 against the action of the spring 79. When the slot 58 registers with the column stop, the stop member 43 will be shot rapidly by the flexed spring 79 to the projected position. 60 This movement of the stop member 43 is so rapid that the column stop does not have an opportunity to pass the abrupt face 57 of the stop 54 and is engaged thereby, the stop 54 at this time acting as a tabulator stop 65 and the stop 50 as an anti-rebound stop.

Otherwise the operation of the tabulator is as previously described.

I have hereinbefore indicated that the stop 34 may or may not be employed, depending on the length of the carriage. 70 When a long carriage is used I prefer to form the bracket arm 21 integral with the retaining plate or foot-piece 18^a. The bracket arm 21 has an integral flat substantially horizontally disposed part 88 provided 75 with a comparatively long slot 89 that extends longitudinally parallel with the column stop bar 26. A plate 90 underlies the part 88 and is adjustably secured thereto by a headed clamping screw 91, the stem 80 of which passes freely through the slot 89 and is received in a tapped opening in the plate 90 to secure the latter in place. The plate 90 carries a rearwardly projecting stop, brace, or finger 92 that overlies and 85 contacts with the upper side of the column stop bar 26. The purpose of this stop or finger 92 is to prevent the column stop bar from being bent or flexed upwardly intermediate its ends when a column stop thereon 90 engages either of the bevel faces 56, 52 and forces the stop member 43 down against the force of the spring 79. Of course it will be understood that the longer the carriage, and consequently the longer the stop bar 26, the 95 more apt the latter is to be bent or flexed in the circumstances pointed out. In carriages of standard length the use of the stop finger 92 may be found unnecessary.

The object of making the plate 90 which 100 carries the finger or brace 92 adjustable in the general direction of the travel of the carriage, is to enable said finger to be adjusted to one side or the other of a column stop in the event that said finger should happen to 105 be at a point on the column stop bar where it is desired to position a column stop.

When the stop or brace 92 is employed it 110 is also desirable to employ the adjustable screw stop 34. In the present instance I prefer to provide a laterally projecting arm 93 on the plate 90. This arm overlies the feed rack 9 and is tapped to receive the screw stop 34, which is held in its adjusted 115 position by a lock nut 94. The lower end of this screw co-acts with the upper edge of the feed rack about midway in the length of the latter to act as a limiting means therefor, as previously described. In long carriages, and in the absence of the stop 34, the 120 upward braking action of the releasing member 83 on the feed rack might tend to bend or flex the latter, so that there would not be a rigid resistance of the rack at the center thereof to the action of the brake 125 shoe, and a defective and unreliable operation of the tabulator might result. However, when shorter standard carriages are used the feed racks are proportionately shorter and there is less liability of the rack 130

being bent or flexed in the action of the releasing device against it.

It will be seen that the key controlled stop member 43 is carried wholly by and slides on the comparatively heavy bracket 38 which is fixed to the frame of the machine. Therefore, the resistance to the impact between the stops, in arresting the carriage, is borne by said bracket and not by the lever 72 or any key controlled part by which the stop 43 is projected to effective position through the interposed spring 79.

It also will be seen that by a simple form of construction motion may be transmitted from the tabulator key at one side of the machine to the stop member 43 located about centrally thereof and that I have provided a highly efficient tabulator, anti-rebound, and brake mechanism which is simple in construction and may be manufactured and assembled in the machine at comparatively small cost. It will be seen, moreover, that the construction is such that it may be readily embodied in existing typewriting machines, such for example as the No. 10, the improved No. 10, the Nos. 11 and 12 Remington machines, without material modification of such machines except by way of substitution of the present tabulating mechanism and carriage retarding mechanism for those formerly employed.

It should be understood that various changes may be made in the construction, and parts thereof may be omitted, without departing from the invention as it is defined in the accompanying claims.

What I claim as new and desire to secure by Letters Patent, is:—

1. In a typewriting machine, the combination of a carriage, escapement mechanism therefor including a feed rack mounted for movement on the carriage to releasing position, a limiting stop for positively arresting the releasing movement of the feed rack, a column stop carried by the carriage, a co-operative tabulator stop, a tabulator key, a spring between said key and tabulator stop and through which the latter is projected to effective position by the actuation of said tabulator key, and a rack releasing device controlled by said tabulator key and operative to press the rack against said limiting stop while the key is maintaining the tabulator stop in its projected position, thus exerting a braking action by the releasing device to retard the movement of the carriage when the tabulator key is maintained depressed.

2. In a typewriting machine, the combination of a carriage, escapement mechanism therefor including a feed rack mounted for movement on the carriage to releasing position, a limiting stop for positively arresting the releasing movement of the feed rack, a column stop, a combined tabulator and anti-rebound stop, a tabulator key for moving

said combined stop into effective position, and a rack releasing device also controlled by said tabulator key and effective to force the rack against said limiting stop after the combined stop has been moved to effective 70 position and thereby cause the releasing device to act as a brake to retard the movement of the carriage from the time the latter is released.

3. In a typewriting machine, the combination of a carriage, escapement mechanism therefor including a feed rack mounted for movement on the carriage to releasing position, a limiting stop for positively arresting the releasing movement of the feed rack, a 80 column stop, a combined tabulator and anti-rebound stop, a tabulator key, a spring between said key and combined stop and through which motion is transmitted from the key to the combined stop, arresting 85 means independent of said key for limiting the motion of said combined stop to effective position, and a rack releasing device controlled by said tabulator key and effective to act as a brake to retard the movement 90 of the carriage.

4. In a typewriting machine, the combination of a carriage, column stops carried thereby, a fixed support carried on the frame of the machine, a one-piece combined tabulator stop and anti-rebound stop mounted and adapted to slide with a rectilinear movement on said support, a tabulator key, a spring interposed between said key and said one-piece combined tabulator stop and anti-rebound stop and through which the latter is moved to effective position to co-act with said column stops, a feed rack mounted for releasing movement on the carriage, limiting means for limiting the releasing movement 100 of said feed rack, and a releasing device controlled by said tabulator key and effective to exert a braking action on the feed rack to retard the carriage in its tabulating movement.

5. In a typewriting machine, the combination of a carriage, column stops carried thereby, a fixed support carried on the frame of the machine, a one-piece combined tabulator stop and anti-rebound stop mounted 110 and adapted to slide with a rectilinear movement on said support, a tabulator key, a lever actuated by said key, a spring carried by said lever and through which motion is transmitted from said lever to said one-piece 115 combined tabulator stop and anti-rebound stop to move it to effective position to co-act with said column stops, a feed rack mounted for releasing movement on the carriage, a stop co-acting directly with said feed rack to limit its releasing movement, and a releasing device carried by said lever and co-acting directly with said feed rack to release it and apply a braking action thereto to retard the 120 carriage.

6. In a typewriting machine, the combination of a carriage, column stops carried thereby, a fixed support carried on the frame of the machine, a one-piece combined tabulator stop and anti-rebound stop mounted and adapted to slide with a rectilinear movement on said support, a tabulator key, a lever actuated by said key, a spring carried by said lever and through which motion is transmitted from said lever to said one-piece combined tabulator stop and anti-rebound stop to move it to effective position to co-act with said column stops, and stopping means between said fixed support and said combined tabulator stop and anti-rebound stop for limiting the movement of the combined stop to effective position.
7. In a typewriting machine, the combination of a carriage, column stops carried thereby, a fixed support carried on the frame of the machine, a one-piece combined tabulator stop and anti-rebound stop mounted and adapted to slide with a rectilinear movement on said support, a tabulator key, and a spring interposed between said key and said one-piece combined tabulator stop and anti-rebound stop and through which the latter is moved to effective position to co-act with said column stops.
8. In a typewriting machine, the combination of a carriage, column stops carried thereby, a fixed support carried on the frame of the machine, a one-piece combined tabulator stop and anti-rebound stop mounted and adapted to slide with a rectilinear movement on said support, a tabulator key, a lever actuated by said key, and a spring carried by said lever and through which motion is transmitted from said lever to said one-piece combined tabulator stop and anti-rebound stop to move it to effective position to co-act with said column stops.
9. In a typewriting machine, the combination of a carriage, column stops carried thereby, a fixed support carried on the frame of the machine, a one-piece combined tabulator stop and anti-rebound stop mounted and adapted to slide with a rectilinear movement on said support, a tabulator key, a lever actuated by said key, a spring carried by said lever and through which motion is transmitted from said lever to said one-piece combined tabulator stop and anti-rebound stop to move it to effective position to co-act with said column stops, and stopping means between said fixed support and said combined tabulator stop and anti-rebound stop for limiting the movement of the latter to effective position.
10. In a typewriting machine, the combination of a carriage, column stops carried thereby, a support fixed on the frame of the machine about centrally thereof, a tabulator stop carried by said support and slidably mounted thereon for movement into and out of effective position and limited in its movement into effective position by said fixed support, a tabulator key lever mounted near one side of the machine, an upwardly extending link connected to said key lever, a sublever pivoted intermediate its ends and extending transversely of the machine and connected at one end to said link, and a leaf spring carried by the other end of said sublever and through which motion is transmitted to said slidably mounted tabulator stop from said sublever.
11. In a typewriting machine, the combination of a carriage, column stops carried thereby, a support fixed on the frame of the machine about centrally thereof, a tabulator stop carried by said support and slidably mounted thereon for movement into and out of effective position, a tabulator key lever mounted near one side of the machine, an upwardly extending link connected to said key lever, and a sub-lever pivoted intermediate its ends and extending transversely of the machine and connected at one end to said link and operatively connected at its other end to said tabulator stop, said sub-lever comprising two parts one of which is adjustable to different set positions relatively to the other part.
12. In a typewriting machine, the combination of a carriage, column stops carried thereby, a support fixed on the frame of the machine about centrally thereof, a tabulator stop carried by said support and slidably mounted thereon for movement into and out of effective position, a tabulator key lever mounted near one side of the machine, an upwardly extending link connected to said key lever, a sub-lever pivoted intermediate its ends and extending transversely of the machine and connected at one end to said link and operatively connected at its other end to said tabulator stop, a feed rack carried by and movable to releasing position on the carriage, and a rack lifting shoe carried by said sub-lever and underlying said feed rack.
13. In a typewriting machine, the combination of a carriage, column stops carried thereby, a support fixed on the frame of the machine about centrally thereof, a tabulator stop carried by said support and slidably mounted thereon for movement into and out of effective position, a tabulator key lever mounted near one side of the machine, an upwardly extending link connected to said key lever, a sub-lever pivoted intermediate its ends and extending transversely of the machine and connected at one end to said link, a spring carried by said sub-lever near the other end thereof and through which direct connection is made with said tabulator stop to move it to effective position.
14. In a typewriting machine, the combination of a carriage, column stops carried thereby, a support fixed on the frame of the

- machine about centrally thereof, a single-piece combined tabulator and anti-rebound stop member co-operative with said column stops to effect ordinary or reverse tabulation and to prevent rebound of the carriage in either direction, said stop member being mounted for sliding movement into and out of effective position on said support, a key lever mounted near one side of the machine, a link connected therewith, a sub-lever connected at one end to said link, and a spring carried by said sub-lever and co-acting directly with said stop member to move it to effective position. 5
- 15 15. In a typewriting machine, the combination of a carriage, column stops carried thereby, a support fixed on the frame of the machine about centrally thereof, a single-piece combined tabulator and anti-rebound stop member co-operative with said column stops to effect ordinary or reverse tabulation and to prevent rebound of the carriage in either direction, said stop member being mounted for sliding movement into and out 10 of effective position on said support, a key lever mounted near one side of the machine, a link connected therewith, a sub-lever connected at one end to said link, a spring carried by said sub-lever and co-acting directly 15 with said stop member to move it to effective position, means for arresting the movement of said stop member to effective position, a feed rack mounted for releasing movement on the carriage, arresting means for limiting the releasing movement of the rack, and a combined feed rack releasing device and 20 brake shoe carried by said sub-lever. 25
16. In a typewriting machine, the combination of a carriage; escapement mechanism therefor including a feed rack mounted for movement on the carriage to releasing position; adjustable stops for limiting such releasing movement of the feed rack; tabulator 30 mechanism including a column stop bar carried by the carriage, an adjustable stop or contact that co-acts therewith intermediate its ends to prevent the column stop bar from being flexed or bent, column stops carried by said bar, a co-operative tabulator stop, a tabulator key therefor, and a rack releasing device controlled by said key and effective to force the rack with more or less force against said limiting stops and to act as a brake to retard the movement of the carriage. 35
17. The combination of a carriage, escapement mechanism therefor including a feed rack mounted on the carriage for movement to releasing position, an adjustable limiting stop for positively arresting the releasing movement of the feed rack, a carriage carried tabulator stop, a counter stop mounted on the frame of the machine for limited movement into the path of the carriage carried stop, a key, a rack releasing lever controlled by said key, a rack lifting shoe on said lever cooperative with said rack to force it into contact with said adjustable stop and effect a braking action on the rack to retard the movement of the carriage, and a leaf spring secured at one end to said rack releasing lever and cooperative with said counter stop to lift it to the limit of its movement into the path of the carriage carried stop during the actuation of said rack releasing lever and thereafter permit a further continued movement of said lever to bring the rack against said adjustable stop and apply a braking action from said rack lifting shoe against the feed rack and thereby retard the carriage more or less depending on the pressure exerted on said key. 40
